UNITED STATES PATENT OFFICE.

WILLIAM KELLER, OF DECATUR, ILLINOIS.

SWITCH-FROG.

1,093,860.

Specification of Letters Patent. Patented Apr. 21, 1914.

Application filed July 25, 1913. Serial No. 781,234.

To all whom it may concern:

Be it known that I, WILLIAM KELLER, a citizen of the United States, residing at Decatur, in the county of Macon and State of Illinois, have invented a new and useful 5 Switch-Frog, of which the following is a specification.

The device forming the subject matter of this application is a switch, so constructed 10 that the main line rails will be unbroken at the frog.

One object of the invention is to provide a novel form of switch so constructed, that, as aforesaid, the main line rails will be un- 15 broken at the frog.

Another object of the invention is to provide a novel means for elevating the wheel of a passing car over one of the main line rails at the frog.

20 The invention aims to provide novel means for operatively connecting the several movable elements of the structure.

It is within the scope of the invention to improve generally and to enhance the utility 25 of devices of that type to which the present invention appertains.

With the above and other objects in view which will appear as the description proceeds, the invention resides in the combination 30 and arrangement of parts and in the details of construction hereinafter described and claimed, it being understood that changes in the precise embodiment of the invention herein disclosed can be made with- 35 in the scope of what is claimed without departing from the spirit of the invention.

In the drawings:—Figure 1 shows the invention in plan; Fig. 2 is a transverse section on the line 2—2 of Fig. 1; Fig. 3 is a 40 perspective view of the elements which co-operate at that portion of the structure where the frog commonly is located; Fig. 4 is a perspective view of the head which is carried by one end of the movable portion 45 of the lead rail; Fig. 5 is a perspective view showing a portion of one of the main line rails and the spacing block carried thereby.

In the accompanying drawings, the number 50 1 indicates the switch ties and the number 2 indicates the stand ties.

One of the main line rails is shown at 3 and the other main line rail is shown at 4, the main line rail 4 being continuous and unbroken at the point of intersection be- 55 tween the said main line rail and the co-operating siding rail 11. The lead rail is

shown at 5 and terminates in a movable switch point 6 which, as shown in Fig. 2 extends upwardly above the upper edge of the main line rail 3, the switch point being beveled at its free, pointed end, as shown at 7.

One of the siding rails is denoted by the reference character 8 and terminates in a movable switch point 9 located outside of the main line rail 4, the switch point 6 being 60 located between the rails 3 and 4 and adjacent the rail 3. The movable switch point 9 upstands above the adjacent main line rail 4, and is beveled at its free end as indicated at 10. The other siding rail is shown 65 at 11 and terminates in a movable extension 12.

Mounted upon certain of the switch ties 1 is a base plate 14 upon which the extension 12 of the siding rail 11 is mounted to slide. 70 The base plate 14 supports a guard rail 15 located inside the main rail 4. Another guard rail 16 is located outside of the main line rail 4 and extends upon the base plate 14. 75

Located opposite to the guard rail 16 and disposed adjacent the siding rail 8 is a guard rail 17.

Secured to the outer face of the main line rail 4 is a filler block 18 which is shown in 80 clearest detail in Fig. 5. The filler block 18 is of approximately wedge shape in horizontal section, and the end of the movable extension 12 of the siding rail 11 is adapted to move in close proximity to the beveled 85 face 19 of the filler block 18.

The lead rail 5 terminates in a movable rail 21, the upper edge of which is elevated above the upper edge of the main line rail 4. Secured to the extremity of the movable 90 rail 21 is a head 22 which is shown in detail in Fig. 4. The head 22 is offset on one side as shown at 23, to receive the end of the movable rail 21, the rail and the head 22 being connected by means of bolts 24 or 100 other attaching elements adapted to a like end. The extremity of the head 22 is cut away as indicated at 25, to form a beveled side face 26, adapted to fit up against the inner edge of the main line rail 4, and to 105 form a flange 27 which is adapted to overhang the upper edge of the main line rail 4.

Located at any suitable point is a stand 28 carrying a shaft 29 supporting pivotally a rotatable element 30. A connection 31 110 unites the rotatable element 30 with the movable extension 12 of the siding rail 11.

Another connection 32 which, like the connection 31 preferably is rigid, is pivotally secured at its outer end to the rotatable element 30, the inner end of the connection 32 terminating in a gooseneck 33 which is pivotally connected with the head 22. The connections 31 and 32 are shown in the present instance as disposed in crossed relation. A link 34 is provided, the same extending approximately parallel to the rails 3 and 4, one end of the link 34 being pivoted to the rotatable element 30, the other end of the link 34 being pivoted to one arm of a bell crank 35 fulcrumed as indicated at 36 upon one of the stand ties 2. A rod 37 is pivoted to the other arm of the bell crank 35, the inner end of the rod 37 being pivotally connected with a brace 38, united with the switch points 6 and 9. A pitman 39 is pivoted to the brace 38 and engages a crank 40 formed upon a shaft 41 provided with a handle 42, the shaft 41 being journaled for rotation in bearings 43 supported by the stand ties 2.

Presupposing that a train is passing along the main line rails 3 and 4 in the direction indicated by the arrow A, or in a direction opposite to that indicated by the arrow A, the parts being disposed as shown in Fig. 1, it is obvious that the rail 4 is unbroken at that portion of the structure which in a standard construction represents the frog. If the free end of the handle 42 is swung toward the main line rail 4, the shaft 41 will be actuated, the crank 40 through the instrumentality of the pitman 39 actuating the brace 38. When the brace is actuated in the manner above described, the switch point 6 will move over into abutment with the side face of the main line rail 3 and the switch point 9 will move over into abutment with the outer side face of the main line rail 4. When a brace 38 is actuated in the manner hereinbefore described, the rod 37 will move, along with the brace, and tilt the bell crank 35 on its fulcrum 36. When the bell crank 35 is tilted, the rod 34 will be actuated, the same rotating the member 30 upon its pivotal support 29. By the rotation of the member 30, the connections 31 and 32 will be actuated. The connection 31 will slide the movable rail 12 toward the main line rail 4 until the end face of the rail 12 is in close proximity to the side face 19 of the filler block 18, the inner edge of the rail 12 being aligned with the side face 20 of the filler block. The connection 32 will swing the head 22 and the movable rail 21 until the beveled face 26 of the head 22 abuts against or is in close proximity to, the inner edge of the main line rail 4 and at the same time, the flange 27 of the head 22 will overlap the main line rail 4, the inner edge of the flange 27 being lined up with the face 20 of the

filler block 18 and with the inner edge of the movable rail 12. Presupposing that the parts are positioned as above described and that a train is moving in the direction of the arrow B, the wheel which is adjacent the main line rail 3 may be elevated by the beveled end 7 of the switch point 6 and the wheel which is adjacent the main line rail 4 will be elevated by a raised, bevel-ended lifting block 44 which is mounted upon the stand ties 2 inside of the main line rail 4. In this manner, the wheels will traverse the switch points 6 and 9, the block 44 serving to elevate the corresponding wheel, so that the same may pass over the upper edge of the main line rail 4. One wheel will traverse the switch point 9 and the siding rail 8, and the other wheel will traverse the switch point 6, the lead rail 5, the movable rail 21 and the head 22. Owing to the fact that the rail 21 at its upper edge is elevated above the main line rail 4, the tread of the wheel will roll along the top of the flange 27 and pass onto the movable rail 12. Presupposing that a train is moving along the siding in the direction of the arrow C, one wheel will traverse the siding rail 8 and the switch point 9. Owing to the fact that the upper edge of the switch point 9 is elevated above the upper edge of the adjacent main line rail 4, the flange of the said wheel will be transferred to the inside of the rail 4, the beveled end 10 of the switch point 9 serving to ease the wheel down onto the main line rail 4 after the flange of the wheel is located inside of the said rail. The other wheel, traversing the siding rail 11 will be elevated by the movable extension 12, and the tread of the wheel will be deposited on top of the flange 27, the flange of the wheel being elevated sufficiently to pass over the main line rail 4. Thence, the wheel will traverse the rail 21, the lead rail 5 and the switch point 6, the beveled end 7 of which will serve to ease the wheel down onto the main line rail 3.

From the foregoing it will be observed that the invention herein disclosed, comprises a structure whereby a train may be shunted readily from the main line to the siding, without opening the main line rail, adjacent what may be denominated the frog, although, in fact, the present invention dispenses entirely with the use of a frog.

The device herein disclosed is of few parts and is simple in construction. Any one of the essential parts of the structure may be replaced readily, when worn or broken, without disorganizing those parts of the device which are intact.

Although the specific means shown for actuating the rails 12 and 21 and the switch points 6 and 9 is a desirable and useful one, it is to be understood that any other suitable means may be employed for this pur-

pose. The block 18 is of importance, since it serves as a brace for the rail 4 and also renders unnecessary a beveling of the end of the rail 12. The rail 12 may be cut off at a right angle at its free end and the block 18 will tend to act as a bridge between the free end of the rail 12 and the rail 4.

Having thus described the invention, what is claimed is:—

- 10 In a device of the class described, a main line rail; a siding rail including a movable extension; a lead rail including a movable end portion adapted to overlap the main line

rail; a fixed filler located between the end of the movable extension and the main line 15 rail; and means for moving the extension and the movable portion of the lead rail into alignment with each other and with the filler.

In testimony that I claim the foregoing as 20 my own, I have hereto affixed my signature in the presence of two witnesses.

WILLIAM KELLER.
